[57] CLAIM

The ornamental design for an in-line multiple fuse holder, as shown and described.

DESCRIPTION

FIG. 1 is an isometric view of an in-line multiple fuse holder according to the new design with cut-to-length wires only partially disclosed for ease of illustration;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is an isometric view of the invention shown in FIG. 1 with the cap open; and,

FIG. 8 is a top view of the invention in FIG. 1 with the cap open.
